UNITED STATES PATENT OFFICE.

CHARLES WHITTINGHAM AND JOSEPH WHITTINGHAM, OF CLEVELAND,
OHIO.

VAPOR-BURNER.

SPECIFICATION forming part of Letters Patent No. 235,600, dated December 14, 1880.

Application filed October 21, 1880. (Model.)

To all whom it may concern:

Be it known that we, CHARLES WHITTINGHAM and JOSEPH WHITTINGHAM, both of Cleveland, in the county of Cuyahoga and 5 State of Ohio, have invented certain new and useful Improvements in Vapor-Burners, which improvements are fully set forth in the following specification and accompanying drawings, in which—

10 Figure 1 is a side elevation. Fig. 2 is a vertical section.

The nature and objects of these improvements will fully appear in the subjoined description, when considered in connection with 15 the accompanying drawings.

A is a perpendicular pipe attached to a pipe leading from an oil-fount. B is a circular plate provided with chambered or hollow ears or projections C D on opposite sides, and 20 which are connected by a conduit, E, across the under side of said plate at one side of the central opening therein. F is a central tube, fixed in the central opening in said plate B. The said plate B is attached, by one of the projections, C, to the aforesaid pipe A.

Depending from the opposite projection, D, is a pipe, G, having an arm, H, with a socket, I, in which the valve-stem J is screwed for controlling the jet-orifice K, located directly 30 under the central tube, F.

L is a socket at the side of the arm I, in which a valve-stem, M, is screwed, closing an opening, O, leading from the pipe H. An outlet, N, is made in the under side of the 35 socket L. The object of the socket L is to supply a means of discharging a quantity of gasoline into the heater-cup P below. Heretofore this has been done by opening the needle-valve and allowing gasoline to flow from 40 the jet-orifice. This has been attended with danger of gasoline spurting up into the tube and burner above and spilling about, while but a portion would fall into the cup. Consequently when fire was set to the gasoline in 45 the cup there was liability of fire taking to the gasoline that had overflowed, and danger resulting therefrom. This danger is overcome, as will be seen, by this device. By unscrewing the valve M a small portion of gasoline 50 falls from the outlet N directly into the cup

underneath, and when said cup is full enough the valve is closed.

Q is a cap or shield, fitted onto the socket I and overspreading the cup P. This is designed to catch the smoke from the burning gasoline in said cup and where said smoke is burned or consumed, and thus prevent the smoking and clogging of the upper part of the burner. 55

Surmounting the plate B is a perforated cap, S. The flames from the lower row of 60 perforations supply heat to the upper surfaces of the chambered projections C and D. These two points are where the generation of vapor takes place, and is therefore perfect, being the 65 hottest place, and without detracting from the heat of the burner for the other uses to which it is designed.

We are aware that a rectangular chamber located between the two jets of flame from the perforated cap has been used, and that 70 said chamber has been connected with an induction oil-pipe and an eduction vapor-pipe; but this has detracted materially from the efficiency of the burner because of its interference with the flames. This objection is entirely overcome by the use of the chambered projections at the side of the perforated combustion-cap, and just below the level of the lower row of flame-jets. 75

We would further add that the use of the 80 cock L is simply to supply a means, independent of the orifice K, for discharging a small quantity of gasoline into the cup below, to avoid the danger of an excess or overflow, as unavoidably occurs when the gasoline is discharged from the orifice K. It shoots upward into the cap, and flowing back spills most of it about, while but a small portion flows back into the cup. This causes flames to burn all over the burner when the gasoline is set fire 85 to in the cup, and is liable to dangerous results. 90

Our device L is not intended for an independent burner for heating the generator, but solely for a safe means of supplying the heater-cup with fluid in first starting up the burner. 95

Having described our invention, we claim—

1. The circular plate B, having the chambered projections C D and connecting-conduit E, and provided with the central tube, F, sur- 100

mounted by the perforated cap S, in combination with the vertical tube A and angular pipe G H and socket I, provided with orifice K, controlled by the valve J, as shown and described, and for the purpose specified.

2. The combination, with the angular pipe G H and socket I, having the orifice K, valve J, and cup P, of the socket L, having openings N and O, and valve M, substantially as shown and described, and for the purpose specified.

3. The combination of the cap or shield Q with the angular pipe G H and socket I, having the orifice K, valve J, and cup P, substantially as shown and described, and for the purpose specified.

CHARLES WHITTINGHAM.
JOSEPH WHITTINGHAM.
